PEGBOARD MOUNTED SUPPORT

Albert J. Enckler, North Olmsted, Ohio, assignor to ABL Associates, Inc., Cleveland, Ohio

Filed Sept. 11, 1975, Ser. No. 602,456

Term of patent 14 years

Int. Cl. D6—04

U.S. Cl. D6—125

Fig. 1

Fig. 3

FIG. 1 is a perspective view of a pegboard mounted support showing my new design;

FIG. 2 is a front elevational view thereof; and

FIG. 3 is a side elevational view thereof.

I claim:

The ornamental design for a pegboard mounted support, as shown and described.
